(57) **CLAIM**

The ornamental design for a speaker as shown and described.

DESCRIPTION

FIG. 1 is a perspective view of a speaker showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of area 9 in FIG. 1; and,

FIG. 10 is an enlarged view of area 10 in FIG. 2.

The broken lines in the drawings are for the purpose of illustrating portions of the speaker and form no part of the claimed design. The dot-dash broken lines in the drawings indicates cutoff boundaries for the enlarged detailed portion views and form no part of the claimed design.
